UNITED STATES PATENT OFFICE

104,685

DESIGN FOR AN AUTOMOBILE

Rust Heinz, Pasadena, Calif.

Application September 28, 1936, Serial No. 65,036

Term of patent 7 years

To all whom it may concern:

Be it known that I, Rust Heinz, a citizen of the United States, residing in the city of Pasadena, county of Los Angeles, State of California, have invented a new, original, and ornamental Design for an Automobile, of which the following is a specification, reference being had to the annexed drawing forming a part thereof.

taken from the right front thereof; and Figure 2 is a similar view taken from the right rear. The left side of the automobile is the same in design as that of the right side. Fig. 3 is a plan view.

I claim:

The ornamental design for an automobile as shown and described.

RUST HEINZ.
